US00D922373S

(12) **United States Design Patent** (10) **Patent No.:** **US D922,373 S**
(45) **Date of Patent:** **** Jun. 15, 2021**

(54) **ELECTRONIC DEVICE**

(71) Applicant: **Samsung Electronics Co., Ltd.**, Suwon-si (KR)

(72) Inventors: **Jungmin Yeo**, Seoul (KR); **Minah Koh**, Seoul (KR); **Hakdo Kim**, Seoul (KR); **Bumsoo Park**, Gwangmyeong-si (KR); **Youngshin Shim**, Seoul (KR)

(73) Assignee: **Samsung Electronics Co., Ltd.**, Suwon-si (KR)

(**) Term: **15 Years**

(21) Appl. No.: **29/677,705**

(22) Filed: **Jan. 23, 2019**

(30) **Foreign Application Priority Data**

Jul. 27, 2018 (KR) 30-2018-0034904

(51) LOC (13) Cl. **14-02**

(52) U.S. Cl.

USPC **D14/341**

(58) **Field of Classification Search**

USPC ..... D14/341-346, 138 AC, 126-128, D14/129-130, 137, 138 AA, 138 AB, D14/138 AD, 138 C, 138 G, 138 R, 147, D14/203.3-203.8, 218, 240, 247, 248, D14/341-347, 315-318, 371, 374, D14/388-389, 420, 426, 496; D10/65 CPC G06F 1/16; G06F 1/1601; G06F 1/1637; H04N 5/64; H05K 5/0204; H05K 5/0017; H05K 5/0217

(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines in the figures depict portions of the electronic device which form no part of the claimed design.

1 Claim, 6 Drawing Sheets
